F. CASABLANCAS.

SPINNING FRAME.

APPLICATION FILED OCT. 15, 1915.

1,213,744.

Patented Jan. 23, 1917.

UNITED STATES PATENT OFFICE.

FERNANDO CASABLANCAS, OF SABADELL, SPAIN.

SPINNING-FRAME.

1,213,744.

Specification of Letters Patent. Patented Jan. 23, 1917.

Application filed October 15, 1915. Serial No. 56,025.

To all whom it may concern:

Be it known that I, FERNANDO CASA-BLANCAS, a subject of the King of Spain, residing at San Olegario 15, Sabadell, Spain, have invented certain new and useful Improvements in Spinning-Frames; and I do hereby declare the following to be a full, clear, and exact description of the invention, such as will enable others skilled in the art 10 to which it appertains to make and use the same.

My present invention relates to improvements in spinning frames, and consists more particularly in improvements in such spinning frames as are shown, for instance, in my prior Patent No. 1,147,676, issued July 20, 1915. Spinning frames of this type consist generally in drawing rollers for operating upon the roving, which they receive 15 from a pair of endless belts actuated from driving rollers, and having their forward ends running about guiding rods or rollers which are located in close proximity to said drawing rollers and direct the fibers tangentially therebetween. In all such prior devices, the guiding elements, which usually consist of rollers or stationary rods, are so 20 relatively placed as to cause great pressure upon the belts at this point, which pressure 25 is transmitted to the roving passing therebetween. This pressure is an unyielding pressure, and in this respect different from that exerted upon the roving by the belts. Moreover, this pressure is apt to increase 30 following upon the accumulation of lint or particles of fiber collecting on the guiding elements, which has the effect of enlarging 35 their diameter and consequently forcing the belts more closely together, and exerting 40 greater pressure on the roving as it passes from between the belts and to the drawing rollers.

The present invention has for an object to eliminate this abnormal pressure from 45 the feeding belts adjacent the guiding elements, and aims to so construct and arrange the belts, guiding elements and associated parts as to insure a uniform, yielding pressure upon the fibers throughout their passage 50 between the belts, thereby producing a thread which is more regular and uniform.

Broadly stated, the invention consists in the provision of belts of a material possessing a high degree of rigidity, and in dispos-

ing the forward ends of these belts close to 55 the drawing rollers with or without the use of guiding elements, which, if used, are located a relatively great distance apart, whereby to afford the belts a clearance space 60 within which they may be permitted to yield as occasion demands. Pressure elements, 65 likewise consisting preferably of stationary rods or revolving rollers, may be employed, either independently or in conjunction with the guiding elements, they being so placed as to engage the outer branches or sides of the belts.

In the accompanying drawings forming a part of this application, and in which similar reference symbols indicate corresponding 70 parts in the several views: Figure 1 is a diagrammatic view of one form of the present invention. Fig. 2 is a similar view illustrating the invention as applied on a spinning frame. Fig. 3 is a slightly modified form of the invention showing the use of the pressure elements. Fig. 4 is a diagrammatic view of a further modification. Fig. 5 is a top plan fragmentary view of a spinning frame with parts removed; and 80 Figs. 6, 7 and 8 show details of the bearings for the rollers.

Referring more particularly to the drawings, 1 and 2 designate the guiding elements and 3 and 4 the usual drawing rollers. 85 Driving rollers 5 and 6 are provided in rear of the guiding elements 1 and 2, and over these rollers and elements are trained the feeding belts 7 and 8. These belts 7 and 8 are of a material possessing a high degree of 90 rigidity, so that said belts will stand out from the guiding elements 1 and 2, as clearly shown in Figs. 1 and 2, thereby affording a clearance space between said guiding elements and permitting the belts 7 and 95 8 to yield at this point in a manner similar to the yielding of the belts between the driving rollers 5 and 6 and said guiding elements. These guiding elements 1 and 2 may be either stationary rods or rollers fitted to 100 revolve as the belts 7 and 8 are driven there-around.

In case the guiding elements are constituted by non-rotatable rods, the passage of the belts 7 and 8 thereover will have a 105 brushing and wiping effect, such as will maintain the same clear at all times and prevent accumulations of lint or other par-

ticles tending to increase their diameter and lessen the clearance space therebetween.

Referring now more particularly to Fig. 3, the guiding elements are here dispensed with, and pressure elements 9 and 10, which may be either rods, rollers, or other devices found practical for this purpose, are provided, and located in contact with the outer branches or sides of the belts 7 and 8, where they will cause the belts to embrace a greater portion of the peripheries of the driving rollers 5 and 6, thus insuring positive driving action. These pressure rods or rollers 9 and 10 in the position shown in Fig. 3, force the belts 7 and 8 more closely into contact than the arrangement shown in Fig. 1, and thereby produce a greater pressure on the roving 13, which pressure, however, is constant and uniform. The pressure elements 9 and 10 are equipped with rings 26 for preventing any side shifting of the belts. In this form of the invention it will be noted that the forward ends of the belts 7 and 8 are unsupported, except by the indirect action of the guiding elements 9 and 10, such construction and arrangement insuring of no abnormal pressure on the roving 13 as the same is thrown forward by the rollers 3 and 4.

In Fig. 4 a modified arrangement is shown, wherein one guiding element, 2, is retained while the companion guiding element is dispensed with, and the forward end of the belt 7 left unsupported at this point. The belt 7 is, however, indirectly supported by the pressure element 9, no corresponding pressure element being provided for the belt 8. It is obvious that the guiding element 1 might be retained and the element 2 dispensed with, the belt 8 in such case being under the influence of the pressure element 10.

In Fig. 6 is shown a bracket having bearings 1' and 2' for receiving the journals of the guiding elements 1 and 2, such bracket being provided with an arm 18 fitting the sleeve 23 on the bearing of the upper drawing roller 3. There is also a rearwardly disposed arm 16 on the bracket 21 connected, as by bolt 24, with the framework 15 of the machine.

In Fig. 7 the bracket is shown provided with bearings 9' and 10' for receiving the ends of the pressure elements 9 and 10, the other parts being similar to what is shown in Fig. 6, and what is already described.

For the modification of the invention shown in Fig. 4, the bracket as illustrated in Fig. 8 is required with a bearing 9' for the pressure element 9 and a bearing 27 for the guiding element 2.

The rolls and other parts heretofore described are supported on bracket 27 in the manner shown in Fig. 1.

It will be readily appreciated that the 65 roving 13, after being received between the driving rollers 5 and 6, will be subjected to a uniform pressure throughout its passage between the belts 7 and 8, which pressure will be the result of the rigidity and elasticity of the material of such belts; such pressure being regulated by the elements 9 and 10 will prevent the fibers from being picked up before being properly delivered to the drawing rollers 3 and 4.

It is obvious that those skilled in the art may vary the details of construction and arrangements of parts without departing from the spirit of my invention, and therefore I do not wish to be limited to such features except as may be required by the claims.

I claim:

1. In a spinning frame, the combination of a pair of endless belts for conducting the roving to the drawing rollers, said belts 85 being slack so as to take a certain convexity due to their own rigidness, a pair of driving rollers for said belts which force the belts against one another producing a strong pressure upon the roving carried by said belts, 90 and means to guide the front curve or loop of said belts arranged so as not to exert a direct pressure upon the part of the belts which holds the roving, in order that the pressure of the belts upon the roving may be 95 soft and resilient.

2. In a spinning frame, the combination of a pair of endless belts for conducting the fibers to the drawing rollers, said belts being slack so as to take the convexity resulting 100 from their own rigidness, a pair of driving rollers that compress said belts and drive them, a pair of guiding rods arranged inside of the front curve or loop of said belts, these rods being sufficiently separated one 105 from the other so as not to exert a pressure upon the parts of the belts which hold the roving.

3. In a spinning frame, the combination of a pair of endless belts for conducting the 110 roving to the drawing rollers, said belts being slack so as to take the convexity resulting from their own rigidness, a pair of driving rollers for said belts, a pair of guiding rods arranged inwardly of the front curve 115 or loop of said belts, said rods being separated one from another so as not to exert any pressure upon the parts of the belts carrying the roving, and a pair of outer rods applied to the outward side of the belts 120 in order to increase the resilient pressure exerted by said belts on the roving.

4. In a spinning frame, the combination of a pair of belts for conducting the roving to the drawing rollers, said belts being slack 125 so as to take the convexity resulting from their own rigidness, a pair of driving rollers for said belts and a pair of outer rods

applied to the outward sides of the belts in order to guide their front curves or loops and to increase the resiliency of said belts.

5. In a spinning frame, the combination of a pair of belts for conducting the roving to the drawing rollers, said belts being slack so as to take the convexity resulting from

their own rigidness, an inward guiding rod for one of said belts, and an outer rod applied to the outward side of the other belt, 15 said rods being arranged to guide the front curves or loops of the belts.

In testimony whereof, I affix my signature.
FERNANDO CASABLANCAS.
